FIG. 1 is a front elevational view of a master link showing our new design;

FIG. 2 is a side elevational view thereof;

FIG. 3 is a top plan view thereof;

FIG. 4 is a bottom plan view thereof;

FIG. 5 is a sectional view taken generally along line 5—5 in FIG. 1;

FIG. 6 is a sectional view taken generally along line 6—6 in FIG. 1; and

FIG. 7 is a sectional view taken generally along line 7—7 in FIG. 1.

The non-illustrated rear and opposite side elevational views of the master link are identical in appearance to the front and side elevational views shown in FIGS. 1 and 2, respectively.

We claim:

The ornamental design for a master link, as shown and described.
